SNAP ACTION DEVICE

Albert E. Baak, Minneapolis, Minn., assignor to
 Minneapolis-Honeywell Regulator Company,
 Minneapolis, Minn., a corporation of Delaware

Application August 4, 1939, Serial No. 288,255

21 Claims. (Cl. 200—83)

This invention relates broadly to snap action mechanisms and more particularly to snap action mechanisms which are operated automatically in response to changes in a variable condition. Snap action mechanisms inherently have a certain differential of operation and the present invention deals particularly with the adjustment of the limits of this differential.

The primary object of the invention is to provide a mechanical snap action mechanism in which the two limits of the differential are adjustable independently of each other.

A further object is to provide a control device which may be biased in one direction against one latch and in the other direction against a second latch in combination with a condition responsive device for alternately tripping the latches.

These and other objects will become apparent as the following specification is read in the light of the accompanying drawing in which

Figure 1 is a more or less diagrammatic view of the snap action mechanism of my invention, and

Figure 2 is a view similar to Figure 1 showing the parts in a different position.

A casing is provided as indicated at 10 for housing the snap action mechanism. Mounted within the casing and at the bottom thereof is a bracket 11 which pivotally carries a lever 12 as indicated at 13. The lever 12 carries a resilient contact blade 14 and a rigid stop arm 15 by means of the rivets 16. The resilient blade 14 carries an electrical contact 17 and is biased into engagement with the stop arm 15 as seen in Figure 2. The lever 12 is also provided with an arm 18 to which is connected one end of a tension spring 19 whose other end is hooked into the bracket 11 to bias the lever 12 for rotation in a counter-clockwise direction. Also mounted at the bottom of the casing 10 is a bracket 20 which is provided at its upper end with a forwardly extending arm 21 which carries a stationary electrical contact 22 with which the movable contact 17 is adapted to engage.

Connected to the side of the casing 10 is a bracket 25 which pivotally supports a latch 26 as indicated at 27. The bracket 25 also carries a leaf spring 28 having a curved end 29 which engages the latch 26 and biases it for rotation in a clockwise direction. Attached to the opposite side of casing 10 is another bracket 30 which pivotally carries the latch 31 as indicated at 32. Bracket 30 also carries a leaf spring 33 engaging the latch 31 and biasing it for rotation in a counter-clockwise direction.

A floating switch actuating lever is indicated at 35. Although no such means has been illustrated, it will be understood that some device is used in connection with this floating lever to prevent it from moving laterally with respect to the casing 10. A second pivoted lever such as is disclosed in applicant's Patent No. 2,266,144 of Dec. 16, 1941, may be used. The lever 35 is provided with an upwardly projecting ear 36 near its end 37 to which is connected one end of a tension spring 38, the other end of the spring being secured to an adjusting nut 39 which is screw-threadedly mounted on the screw 40. Screw 40 projects loosely through the hole 41 in the top of the casing 10 and is provided with a flanged head 42 having a kerf 43 by means of which it may be rotated. The nut 39 is provided with an outwardly extending arm 44 which projects through a slot 45 in the side of the casing 10 to prevent rotation of the nut 39 as the screw 40 is rotated. As a result of this construction, rotation of the screw 40 will vertically adjust the nut 39 and hence adjust the tension of the spring 38. If desired a scale may be applied to the outside of the casing 10 adjacent the slot 45 in order to indicate the adjustment of the spring 38.

The end 47 of lever 35 is provided with an ear 48 to which one end of spring 49 is connected. The other end of this spring is secured to the adjusting nut 50 which is screw-threadedly mounted on the screw 51. The screw 51 projects loosely through the hole 52 in the top of the casing 10 and is provided with a flanged head 53 having a kerf 54. The nut 50 is provided with an arm 55 projecting outwardly through slot 56 in the side of casing 10. The spring 49 is therefore adjusted by the screw 51 in the same manner as the spring 38 and a scale may be applied to the outside of the casing 10 adjacent the slot 56 to indicate the adjustment of the spring 49. The springs 38 and 49 normally hold the lever 35 in its upper position adjacent the stops 58 and 59 as seen in Figure 2.

Suspended from the top of casing 10 is a bellows 60 which is connected by means of a capillary tube 61 to a thermal device or a source of variable pressure, depending upon whether it is desired that this bellows respond to changes in temperature or changes in pressure. At its lower end the bellows 60 carries a pointed operating member 62 which engages a bearing 63 carried by the mid portion of the lever 35. On expansion of the bellows, the lever 35 is moved downwardly and this position is limited by means of the stops 58 and 66.

The end 37 of lever 35 is provided with a downwardly extending ear 68 which carries an insulating pusher 69 which under certain circumstances engages an arm 70 on the lever 12 to engage it with the shoulder 71 on latch 26. The resilient contact blade 14 has an upturned end 72 which under certain circumstances engages the shoulder 73 on the latch 31.

In considering the operation of the above described device, let it be assumed first that the temperature or pressure to which the bellows 60 responds is at a predetermined low value and that the bellows 60 is in its contracted position as shown in Figure 2. Under these circumstances, the adjusting springs 38 and 49 will hold the lever 35 in engagement with the stops 58 and 59. It will be seen that at this time the end 37 of the lever 35 has cammed the latch 26 to its inoperative position and that the end 47 of lever 35 has disengaged the latch 31 and the spring 33 has rotated this latch until it is in a position where the end 12 on the resilient contact blade 14 may engage the shoulder 73 of the latch when the lever 12 is rotated in a clockwise direction. It will be further noted that the biasing spring 19 has rotated the lever 12 to the position where the contacts 17 and 22 are in open circuit position. The rotation of the lever 12 under the influence of the spring 19 is limited by the stop 75. In order for this mechanism to function in the desired manner, the spring 49 must exert a greater force than the spring 38.

Under these circumstances as the bellows 60 begins to expand in response to an increase in temperature or pressure, it will first rotate the lever 35 in a clockwise direction so that the end 37 will leave the stop 58 against the force exerted by the spring 38. This will release the latch 26 which will then be rotated in a clockwise direction by means of its biasing spring 28. As the end 37 of the lever 35 continues to move downwardly, the insulating pusher 69 will engage the extension 70 on the lever 12 and rotate the lever to its circuit closed position. The stop 65 will prevent further movement of the end 37. At this time, the end 72 of the resilient contact blade 14 will have engaged the shoulder 73 of the latch 31 which will prevent the closure of the contacts 17 and 22. They will be biased to closed position, however, due to the flexing of the contact blade 14 as shown in Figure 1. On a further increase in temperature or pressure, the bellows will continue to expand and start the end 47 of the lever 35 moving in a downwardly direction. The end 47 will engage the latch 31 and cam it out of engagement with the end 72 of the resilient contact blade 14 permitting the contacts 17 and 22 to close with a snap action. The end 47 will continue to move downwardly until it engages the stop 66 as shown in dotted lines in Figure 1.

On a decrease in the temperature or pressure to which the bellows 60 responds, it will contract and raise the end 47 of the lever 35 releasing the latch 31. This movement of the lever 35 has no effect upon the switch contacts 17 and 22. Further contraction of the bellows 60 will raise the end 37 of the lever 35 which will raise the pusher 69 and permit the extension 70 of the lever 12 to engage the shoulder 71 on the latch 26 thereby preventing the lever 12 from rotating in a direction to cause the disengagement of the contacts 17 and 22. On further upward movement the end 37 will cam the lever 26 in a counter-clockwise direction until the shoulder 71 releases the extension 70 of the lever 12 permitting the

biasing spring 19 to snap the lever in a counter-clockwise direction opening the contacts 17 and 22 and returning the parts to the position shown in Figure 2.

5 The temperature or pressure value at which the end 37 of the lever 35 is moved downwardly and upwardly by the bellows 60 is determined entirely by the tension of the spring 38. The adjustment of the spring 49 does not affect this operation materially due to the fact that when the end 37 is being moved the lever 35 is pivoting about the stop 59 which is located so close to the ear 48 to which the spring 59 is connected to the lever 35 that the force exerted by this spring has substantially no rotative effect upon the lever 35. It will be seen in connection with the description of the operation of this device that the movement of the end 37 causes opening of the switch contacts 17 and 22. Therefore by adjusting the spring 38 the temperature or pressure value at which the switch is opened may be adjusted.

Likewise, the temperature or pressure value at which the end 47 is moved is determined entirely by the adjustment of the tension of the spring 49. Movement of this end of the lever 35 controls the closing of the contacts 17 and 22. Therefore by adjusting the tension of the spring 49, the temperature or pressure value at which these contacts are closed may be independently varied.

25 It will therefore be seen that I have provided a switch which is opened and closed by means of a mechanical snap action wherein the temperature or pressure values at which the switch is opened 30 may be independently varied as well as the temperature or pressure values at which the switch is snapped closed.

35 As certain changes and modifications of this invention will occur to those who are skilled in the art, I wish it to be understood that I am to be limited by the scope of the appended claims and not by the specific embodiment disclosed.

I claim as my invention:

40 1. A snap action device comprising in combination, a control member, a first means for biasing said control member for movement in one direction, a first holding device preventing such movement, a second means for biasing said control member for movement in the other direction, 45 a second holding device for preventing such movement, and condition responsive means for alternately tensioning said biasing means and releasing said holding devices.

45 2. A snap action device comprising in combination, a control member, a first means for biasing said control member for movement in one direction, a first holding device preventing such movement, a second means for biasing said control member for movement in the other direction, 50 a second holding device for preventing such movement, condition responsive means for alternately tensioning said biasing means and releasing said holding devices, and means for adjusting the differential of operation of said snap action device.

55 3. A snap action device comprising in combination, a control member, a first means for biasing said control member for movement in one direction, a first holding device preventing such 60 movement, a second means for biasing said control member for movement in the other direction, a second holding device for preventing such movement, condition responsive means for alternately tensioning said biasing means and releasing said holding devices whereby said control

member is snapped first in one direction and then the other, and means for individually and independently varying the condition value at which said control member is snapped in each direction.

4. A snap action device comprising in combination, an actuating member, a condition responsive device associated with said member to move first one end and then the other end of said actuating member, a control device, a mechanical snap action device actuated by one end of said actuating member for moving said control device in one direction with a snap action, means preventing the return of said control device to its original position, and means actuated by the other end of said actuating member for disabling said last mentioned means.

5. A snap action device comprising in combination, an actuating member, a condition responsive device associated with said member to move first one end and then the other end of said actuating member, a control device, a mechanical snap action device actuated by one end of said actuating member for moving said control device in one direction with a snap action, and means controlled by the other end of said actuating member for returning said control device to its original position.

6. A snap action device comprising in combination, an actuating member, a condition responsive device associated with said member to move first one end and then the other end of said actuating member, a control device, a mechanical snap action device actuated by one end of said actuating member for moving said control device in one direction with a snap action, and snap action mechanism controlled by the other end of said actuating member for returning said control device to its original position with a snap action.

7. A snap action device comprising in combination, an actuating member, a condition responsive device associated with said member to move first one end and then the other end of said actuating member, a control device, a mechanical snap action device actuated by one end of said actuating member for moving said control device in one direction with a snap action, means preventing the return of said control device to its original position, means actuated by the other end of said actuating member for disabling said last mentioned means, and means for independently adjusting the condition value at which each end of said actuating member is moved by said condition responsive device.

8. A snap action device comprising in combination, an actuating member, a condition responsive device associated with said member to move first one end and then the other end of said actuating member, a control device, a mechanical snap action device actuated by one end of said actuating member for moving said control device in one direction with a snap action, means controlled by the other end of said actuating member for returning said control device to its original position, and means for independently adjusting the condition value at which each end of said actuating member is moved by said condition responsive device.

9. A snap action device comprising in combination, an actuating member, a condition responsive device associated with said member to move first one end and then the other end of said actuating member, a control device, a mechanical snap action device actuated by one end

of said actuating member for moving said control device in one direction with a snap action, snap action mechanism controlled by the other end of said actuating member for returning said control device to its original position with a snap action, and means for independently adjusting the condition value at which each end of said actuating member is moved by said condition responsive device.

10. A device of the character described comprising in combination, a movable member, a movable contact carried thereby by means of a resilient mounting, a stationary contact positioned to be engaged by said movable contact, means continuously biasing said movable member to contact open position, means for moving said member to contact closed position against the action of said biasing means, a first latch for holding said movable contact in open position by pressing back its resilient mounting, a second latch for holding said member in contact closed position, and means for tripping said first latch and then said second latch.

11. A device of the character described comprising in combination, a movable member, a movable contact carried thereby by means of a resilient mounting, a stationary contact positioned to be engaged by said movable contact, means continuously biasing said movable member to contact open position, means for moving said member to contact closed position against the action of said biasing means, a first latch for holding said movable contact in open position by pressing back its resilient mounting, a second latch for holding said member in contact closed position, means for tripping said first latch and then said second latch, said last named means being actuated by a condition responsive device, and means for varying the differential between the condition values at which each latch is tripped.

12. A device of the character described comprising in combination, a movable member, a movable contact carried thereby by means of a resilient mounting, a stationary contact positioned to be engaged by said movable contact, means continuously biasing said movable member to contact open position, means for moving said member to contact closed position against the action of said biasing means, a first latch for holding said movable contact in open position by pressing back its resilient mounting, a second latch for holding said member in contact closed position, means for tripping said first latch and then said second latch, said last named means being actuated by a condition responsive device, and means for independently adjusting the condition value at which each latch is tripped.

13. An automatic switching device comprising in combination, a movable member, a movable contact resiliently carried thereby, a stationary contact adapted to be engaged by said movable contact, means biasing said member to contact open position, an actuating member, a condition responsive device for first moving one end of said actuating member in response to a change in the condition value which moves said movable member against its bias and latches it on a first latch, and a second latch for holding said movable contact in open position against the force exerted by its resilient mounting, a further change in said condition value causing said condition responsive device to move the other end of said actuating member to trip said second latch and hence close said contacts, a reversal

in said condition change causing said condition responsive device to first move the said other end of said actuating member and then the said one end to trip said first latch and permit said movable member to move to open contact position under the influence of its bias.

14. An automatic switching device comprising in combination, a movable member, a movable contact resiliently carried thereby, a stationary contact adapted to be engaged by said movable contact, means biasing said member to contact open position, an actuating member, a condition responsive device for first moving one end of said actuating member in response to a change in the condition value which moves said movable member against its bias and latches it on a first latch, and a second latch for holding said movable contact in open position against the force exerted by its resilient mounting, a further change in said condition value causing said condition responsive device to move the other end of said actuating member to trip said second latch and hence close said contacts, a reversal in said condition change causing said condition responsive device to first move the said other end of said actuating member and then the said one end to trip said first latch and permit said movable member to move to open contact position under the influence of its bias, and means for varying the difference between the condition values at which each end of said actuating member is moved.

15. An automatic switching device comprising in combination, a movable member, a movable contact resiliently carried thereby, a stationary contact adapted to be engaged by said movable contact, means biasing said member to contact open position, an actuating member, a condition responsive device for first moving one end of said actuating member in response to a change in the condition value which moves said movable member against its bias and latches it on a first latch, a second latch for holding said movable contact in open position against the force exerted by its resilient mounting, a further change in said condition value causing said condition responsive device to move the other end of said actuating member to trip said second latch and hence close said contacts, a reversal in said condition change causing said condition responsive device to first move the said other end of said actuating member and then the said one end to trip said first latch and permit said movable member to move to open contact position under the influence of its bias, and spring means for individually adjusting the condition value at which each end of said actuating member is moved.

16. An automatic switch comprising in combination, a pivoted lever, a resilient contact blade carried thereon, a stationary contact cooperating with said contact blade to close an electric circuit, means biasing said lever to open circuit position, first and second latches, and a condition responsive device which in response to a first condition value rotates said lever to closed circuit position and latches it in this position by said first latch while said second latch holds said resilient contact blade in open circuit position, said condition responsive device in response to a second condition value tripping said second latch and on a return to said first condition value tripping said first latch.

17. An automatic switch comprising in combination, a pivoted lever, a resilient contact blade

carried thereon, a stationary contact cooperating with said contact blade to close an electric circuit, means biasing said lever to open circuit position, first and second latches, a condition responsive device which in response to a first condition value rotates said lever to closed circuit position and latches it in this position by said first latch while said second latch holds said resilient contact blade in open circuit position, said condition responsive device in response to a second condition value tripping said second latch and on a return to said first condition value tripping said first latch, and means for independently adjusting said condition values.

18. In a device of the character described, a switch member movable between open and closed positions, a first latching means to prevent movement of said switch to closed position, a second latching means to prevent movement of said switch to open position, a condition responsive device alternately cocking and tripping said two latching means to move said switch member between open and closed positions with a snap action, a support independent of the movable parts of said device, and means mounted on said support for varying the difference between the condition values at which said switch is actuated to open and closed positions.

19. In a device of the character described, a switch member movable between open and closed positions, a first latching means to prevent movement of said switch to closed position, a second latching means to prevent movement of said switch to open position, a condition responsive device alternately cocking and tripping said two latching means to move said switch member between open and closed positions with a snap action, a support independent of the movable parts of said device, and means mounted on said support for varying the condition value at which said switch is actuated to one position independently of the condition value at which it is actuated to the other position.

20. In a device of the character described, a first member pivoted at a point between its ends, a contact resiliently mounted upon one end thereof, a pair of latches adjacent the ends of said first member, one of said latches engaging said contact to prevent rotation thereof in one direction and the other of said latches engaging said first member to prevent rotation thereof in the opposite direction, means biasing said member in one direction, and means for moving said member in the opposite direction against said bias comprising, an elongated second member biased at its ends away from said first member, means associated with the ends of said second member for actuating said latches, means associated with one end of said second member for moving said first member, and condition responsive means for moving said second member.

21. In a device of the character described, a first member pivoted at a point between its ends, a contact resiliently mounted upon one end thereof, a pair of latches adjacent the ends of said first member, one of said latches engaging said contact to prevent rotation thereof in one direction and the other of said latches engaging said first member to prevent rotation thereof in the opposite direction, means biasing said member in one direction, and means for moving said member in the opposite direction against said bias.

ALBERT E. BAAK.
